WASTE RECEPTACLE

Louis J. Martino, Lombard, Wayne E. Moll, Villa Park, and Ralph E. Weimer, Lombard, Ill., assignors to McDonald's System, Inc., Chicago, Ill., a corporation of Illinois

Filed Jan. 21, 1965, Ser. No. 83,504

Term of patent 14 years

(Cl. D58—17)

FIG. 1 is a front perspective view of a waste receptacle showing our new design; and

FIG. 2 is a rear perspective view thereof.

We claim:

The ornamental design for a waste receptacle, substantially as shown.
